UNITED STATES PATENT OFFICE

ADOLPH W. RYBECK, OF MILWAUKEE, WISCONSIN, ASSIGNOR TO T. L. SMITH COMPANY, OF MILWAUKEE, WISCONSIN, A CORPORATION OF WISCONSIN

LOADING SKIP

Application filed October 12, 1928. Serial No. 312,063.

This invention relates to certain new and useful improvements in skip hoists and refers more particularly to skips of the type especially used with concrete mixers, paving machines and the like.

In skips of this nature, and particularly where they are used in connection with large paving machines and the like, the load is appreciable and places excessive strains on its 10 hoisting elements, especially during the initial raising of the skip at which time the inertia is greatest and the degree of leverage is at its minimum, and therefore this invention has as an object the provision of means 15 for increasing the lifting power of the hoist at the time of initial raising of the skip.

Another object of this invention resides in the provision of means for increasing the effective lifting force of the hoisting mechanism of a device of the character described 20 which is so designed as to require but a relatively minor change in the usual construction of such hoisting mechanisms.

This invention has as another object the 25 provision of means for increasing the lifting power of a hoisting mechanism for skips of the character described which also obviates the usual spring shock absorbing means heretofore employed to cushion the shock 30 incidental to the skip reaching its load receiving position.

A further object of this invention resides in the provision of a sheave positioned upwardly of the sheaves carried by the skip 35 and about which the hoisting cable passes, to reduce the load on the hoisting elements at the time of initial upward movement.

And a still further object of this invention resides in the provision of means for 40 increasing the lifting force of a hoisting mechanism of the character described which automatically becomes ineffective after a predetermined movement of the skip whereby maximum lifting force is obtained with a 45 minimum loss of time.

With the above and other objects in view which will appear as the description proceeds, my invention resides in the novel construction, combination and arrangement of parts substantially as hereinafter described 50 and more particularly defined by the appended claims, it being understood that such changes in the precise embodiment of the herein disclosed invention may be made as come within the scope of the claims. 55

In the accompanying drawing, I have illustrated one complete example of the physical embodiment of my invention constructed according to the best mode I have so far devised for the practical application of the 60 principles thereof, and in which:

Figure 1 is a side elevational view of a portion of a machine illustrating my invention as applied thereto;

Figure 2 is a view taken on the plane 65 of the line 2—2 of Figure 1, and

Figure 3 is a detail view of the sheave block detached from the skip.

Referring now more particularly to the accompanying drawing, in which like numerals designate like parts, 5 represents the base of a paving machine, concrete mixer or the like from which frame members 6 extend upwardly to support the various instrumentalities of the machine. Gusset plates 7 70 connect adjacent frame members 6 and provide a pivotal support 8 for the mounting arm 9 of a skip 10, consisting of the usual load receiving body or portion 11 and a discharge chute 12, the mounting arm there- 80 of being riveted or otherwise secured to the skip adjacent chute 12.

As is customary in devices of this nature, the skip is adapted to be moved from its load receiving position illustrated in full 85 lines in Figure 1 to a position shown in dotted lines discharging its load into the mixing drum 13 of the machine, movement of the skip is effected through the medium of a hoisting cable 14, the ends of which 90

are connected with drums 15 fixed on the ends of a shaft 16 mounted in suitable bearings, not shown, carried by the frame and carrying a drive pulley 17. A cable 18 having one end connected with the pulley 17 is wound thereon and has its other end fixed to a drum 19 on which it is wound when it is desired to raise the skip. The drum 19 receives its drive from a shaft 19' connected with the machine power plant, not shown, and adapted to provide the drive for the drum 13.

Heretofore, the medial portion of cable 14 passed over a pair of sheaves 20 mounted between supporting members 21 pivotally connected with the skip proper by straps 22, a pivot rod 23 and supporting members 24, so that as the ends of the cable were wound on their respective drums 15, the skip was elevated.

It will be readily apparent that excessive strains are placed on the hoisting elements of the machine at the time of initial raising of the skip, as the leverage is at a minimum point, and to reduce the load the present invention contemplates the use of an additional sheave 25 carried by a sheave block 26 and over which that stretch of the cable 14 between the sheaves 20 passes. The sheave block 26 is further provided with a pulley 27 at its inner end about which a cable or chain 28 is trained, the ends of which are secured to anchoring members 29 connected with the upper portion of the frame members 6 to support the sheave block 26 and consequently the sheave 25 in a position upwardly of the sheaves 20. Thus it will be seen that a substantial percentage of the load is carried by the chain 28 and that the hoisting mechanism is materially relieved of the stresses imposed at the time of initial raising.

The point at which the sheave 25 is positioned governs the duration of time during which it is effective, for as the skip moves upward, the distance between the sheave 25 and the sheaves 20 decreases to a point (shown in dotted lines in Figure 2) at which the sheave 25 is in line with the sheaves 20 when the pull is directly on the sheaves 20. From this point to the discharging position, the chain 28 is slack and the block 26 is positioned between the members 21 where it remains until the skip, in its downward movement, again reaches this point. As the skip is lowered, the sheave 25 gradually becomes effective and thus acts as a shock absorbing means to ease or cushion the return of the skip to its load receiving position.

From the foregoing description taken in connection with the accompanying drawing, it will be readily apparent to those skilled in the art to which an invention of the character described appertains, that I pro-

vide novel means for reducing the strain on the hoisting mechanism for skips at the time of greatest inertia, which does not materially reduce the speed of operation and which cushions the return of the skip.

70

What I claim as my invention is:

1. In combination with a loading skip adapted to be raised and lowered, cable means for raising the skip, and substantially fixed means about which the cable is trained to partially support the skip during part of its movement, and said means being so located as to become ineffective after a predetermined movement of the skip.

75

2. In combination with a loading skip adapted to be raised and lowered, a pair of sheaves carried by the skip, a cable trained about said sheaves for raising the skip, an auxiliary sheave intermediate said pair of sheaves over which the cable passes, and flexible means for supporting the auxiliary sheave in the path of movement of the skip, whereby the skip is partially supported by said auxiliary sheave and its supporting means and the auxiliary sheave and its supporting means becomes ineffective after a predetermined movement of the skip.

80

3. In combination with a structure to be moved, a cable having its medial portion engaged with the structure at spaced points, means for applying tension to the cable ends to move the structure, a member engaged with the cable at a point intermediate said spaced points, and flexible means for holding the member in the path of travel of said structure to assist the means for applying tension to the cable ends in moving the structure until the structure overtakes the member, continued movement of the structure carrying the member with it.

85

4. In combination with a loading skip adapted to be elevated from load receiving to charging position, means for elevating the loading skip including a cable having its medial portion engaged with the skip at spaced points, means for applying tension to the cable ends to elevate the skip, an auxiliary support engaged with the cable at a point intermediate its points of engagement with the skip and flexible means for holding the auxiliary support in the path of travel of the skip to partially support the weight of the skip during its movement from load receiving position to the point in its travel where it overtakes the auxiliary support, at which time the auxiliary support becomes ineffective and moves with the skip.

90

5. In combination with a loading skip adapted to be lowered to and raised from a position of maximum load, means for raising the skip including a cable connected with the skip at spaced points thereon, an auxiliary cable support with which the cable engages intermediate said points and means normally supporting the auxiliary cable

support medially of the ends of the distance of travel of the skip whereby the raising force applied by the cable is greatest during maximum load and whereby the speed of the skip accelerates as it approaches the auxiliary support.

6. In combination with a loading skip adapted to be lowered to and elevated from a position of maximum load, sheaves carried by the skip, an auxiliary sheave, means normally supporting the auxiliary sheave, a cable trained about the sheaves for elevating the skip, the skip having a predetermined distance of travel, and the auxiliary sheave being located medially of the ends of said distance of travel whereby the elevating force applied by the cable is greatest during maximum load and whereby the speed of the skip accelerates as it approaches the auxiliary sheave.

7. In a loading skip adapted to be raised and lowered, sheaves carried by the skip, an auxiliary sheave, means normally supporting the auxiliary sheave, a cable trained about the sheaves for raising the skip, the skip having a predetermined distance of travel during raising and lowering, and the auxiliary sheave being located medially of the ends of said distance of travel and in a plane between the sheaves carried by the skip, whereby the raising force applied by the cable is greatest at the initial raising of the skip and whereby the speed of the skip accelerates as it approaches the auxiliary sheave, said auxiliary sheave moving with the skip throughout the remainder of the distance of travel.

8. In a charging skip of the character described, a frame, a shaft mounted on said frame, a pair of spaced drums mounted on said shaft, a pair of spaced sheaves mounted on said skip, a hoisting cable attached at the ends thereof to said drums and trained around said sheaves, a pair of flexible supporting members attached to said frame at spaced points and connected at the lower end of said members with the portion of said cable intermediate said sheaves and remote from the line joining said sheaves when said skip is in lowered position.

9. In a device to raise and lower material, a frame, a drum rotatably mounted on said frame, a cable attached at one end to said drum and engaging the device at spaced points intermediate the ends of said cable, means flexibly supported from said frame engaging said cable intermediate said spaced points and holding that portion of the cable between said spaced points above the lowermost position of said device.

10. In a changing skip of the character described, a frame, a drum rotatably mounted on said frame, a pair of spaced sheaves mounted on said skip, a hoisting cable attached at one end thereof to said

drum and trained around said sheaves intermediate the ends of said cable, a pair of flexible supporting members attached to said frame at spaced points and connected at the lower end of said members with the portion of said cable intermediate said sheaves and remote from the line, joining said sheaves when said skip is in lowered position.

In testimony whereof I have hereunto affixed my signature.

ADOLPH WM. RYBECK.
